UNITED STATES PATENT OFFICE.

RICHARD STANFORTH, OF ROCHESTER, NEW YORK, ASSIGNOR TO ART IN BUTTONS, INC., OF ROCHESTER, NEW YORK, A CORPORATION OF NEW YORK.

METHOD OF PRODUCING BUTTONS OR BLANKS FOR DISKS, BUTTONS, OR THE LIKE, FROM IRREGULARLY-SHAPED PIECES OF MATERIAL.

Application filed April 9, 1923. Serial No. 631,047.

The present invention relates to a method of producing buttons, or blanks for disks, buttons or the like, from irregularly shaped pieces of material, and an object of the in-

vention is to provide a method by which it is possible to obtain directly, from the irregularly shaped pieces, complete blanks, or buttons, each being of the maximum desirable size obtainable from an irregularly

shaped piece from which it is formed. Another object of the invention is to provide a method by which it is possible to obtain directly, from the irregularly shaped pieces, complete blanks, or buttons, each being of

the maximum desirable size obtainable from an irregularly shaped piece from which it is formed and containing in a large percentage of cases a plurality of proposed buttons, or blanks for disks, buttons, or the

like. Still another object of the invention is to provide for defining, in each irregularly shaped piece, a blank, or button, of the maximum desirable size obtainable from an irregularly shaped piece from which it is

formed and to thereafter present the irregularly shaped piece to the cutting machine, in such a manner that the blank, so defined, will be cut by such cutting machine. A further object of the invention is to de-

fine in each irregularly shaped piece, a button or blank of the maximum desirable size obtainable from the irregularly shaped piece from which it is formed, and there-

after to cut the blank previously defined with a formed surface on either one or both sides thereof parallel with the plane of the blank. Still another and fur-

ther object of the invention is to provide a method by which it is possible to obtain directly, from irregularly shaped pieces, complete buttons or blanks containing the maximum possibilities in buttons or blanks for disks, buttons, or the like, of the irregularly shaped pieces, regardless of the plane

or axis of such irregularly shaped piece.

To these and other ends, the invention consists of certain steps and combinations of steps in a method of producing buttons, or blanks for disks, buttons, or the like, from irregularly shaped pieces of material, all of

which will be hereinafter described and the novel features pointed out in the appended claim.

In the drawings:

Figs. 1, 2 and 3 show typical irregularly 55 shaped pieces of material cut from the so-called "ivory" nut;

Figs. 4, 5 and 6 are fragmentary views of a classifying device, showing the manner in which buttons, or blanks of maximum de- 60 sirable size are defined in the pieces illustrated in Figs. 1, 2 and 3;

Fig. 7 is a detail view showing the manner in which the irregularly shaped pieces each having the proposed button or blank 65 defined therein are fed to the cutting machine;

Fig. 8 is a fragmentary perspective view of the feeding tube;

Fig. 9 is a detail view showing a plural 70 blank produced by the cutting machine, two buttons being illustrated in dotted lines; and

Fig. 10 is a view of a plural blank showing another manner in which two buttons 75 may be formed therefrom.

For the purpose of illustrating this invention, it will be described as employing irregularly shaped pieces such as the so-called "ivory" nut pieces illustrated in the 80 drawings, but it will be understood that the invention is not limited to this source for the irregularly shaped pieces. These irregularly shaped pieces are, according to this invention, each mechanically tested and 85 classified for the maximum desirable size of a button or circular blank obtainable therefrom, the circular blanks preferably having a thickness which, in most cases, is sufficient to produce a plurality of buttons, or other articles yieldable from the irregularly shaped pieces. When using irregularly shaped material, such as the nut pieces illustrated in the drawings, the diameter of the blanks obtainable therefrom is 90 dependent upon the thickness of such blanks and vice versa, so that if buttons, or other articles of maximum diameter are desired, these may be obtained by testing for and cutting each irregularly 95 100

shaped piece to yield a single button, or blank of minimum thickness, whereas, if the largest number of buttons, or buttons of maximum thickness are desired, these may be obtained by testing for and cutting the blanks in the first instance to the maximum thickness for the irregularly shaped pieces with the diameters of the blanks decreased correspondingly. The expression "maximum desirable" as used in connection with the size of or yield in buttons, or blanks for disks, buttons, or the like, from the irregularly shaped pieces means yield of maximum value, which is governed by trade or market conditions and may be either of the extremes mentioned hereinbefore or any demand in between these extremes.

For carrying on the testing or classifying operations, it is preferred to employ separate means or units for testing the irregularly shaped pieces for each of the size classes or divisions. Each of these testing means, preferably has four spaced gauging points *a*, *b*, *c* and *d*, two of which (*a* and *c*) will cooperate with the major side, such as the skin side 5 of an irregularly shaped nut piece and are spaced apart a distance *e* equal to a predetermined diameter of a button or blank, while the other two (*b* and *d*) are spaced apart a like distance and will cooperate with faces opposed to the skin or major side, the distance *e* of the last mentioned two gauging points from the first mentioned two gauging points being equal to a predetermined thickness at which it is desired to classify the irregularly shaped pieces as to diameter.

It is apparent that in order to secure the different classes that the distances between the gauging points *a*, *b*, *c* and *d* must be varied. A variation in the diameter of the proposed button or blank to be formed from the irregularly shaped pieces is obtained by varying the distance *e* between *a* and *c* and also between *b* and *d*, whereas the variation in the thickness of the proposed button or blank is obtained by varying the distance *e'* between *a* and *b*, and *c* and *d*. This makes it possible to obtain any desired number of different classes, those irregularly shaped pieces rejected in one testing operation being subjected to a succession of other testing operations until the proper class is reached.

An apparatus for testing and classifying the irregularly shaped pieces may consist of a plurality of movable testing or classifying elements such as rotary drums, only fragments *n* being shown, each of which has its walls 10 formed with a plurality of openings 11, the wall of each opening having the four spaced gauging points *a*, *b*, *c* and *d* hereinbefore mentioned. The gauging points of all the openings of any one drum are arranged the same distances apart, but these distances vary in the different drums.

It is apparent that rotation of the drum will subject each irregularly shaped piece therein to a number of different tests to determine whether such piece contains a button or blank of a diameter and thickness greater or less than that defined by the gauging points of the drum.

In forming these buttons, or blanks, defined by the testing operations, a turning or cutting machine of known construction may be employed, which is so adjusted that it will produce a button or blank having a thickness and diameter defined by the testing operations. In order that the blank defined by the testing operations may be cut from the irregularly shaped pieces by the turning machines, the irregularly shaped pieces should be placed in the holding means of the turning machine in a position determined by the measuring operations.

With the end in view of securing this result, for each class of the irregularly shaped pieces, there may be provided a feeding mechanism corresponding to such class. This feeding mechanism, in this instance, embodies a feeding tube which has four guides *a'*, *b'*, *c'* and *d'* spaced apart in the same manner and at the same distances as the gauging points *a*, *b*, *c* and *d*, which define the class of the pieces. These guides lead to the holding means in such a manner that the holding means engages each piece and sustains it in position on the turning machine, so that the turning machine will cut from each piece the blank defined by the testing operation. In cutting buttons or blanks from irregularly shaped pieces formed from nuts, the cutting tool 2 preferably operates from the sawed side 3 of the piece, while the piece is held in any suitable manner, as by the plunger 4, within the area of the proposed button or blank preferably with the skin side 5 engaging a plurality of gauging points 6, whereby the plane of the blank 7 obtained from the irregularly shaped piece will be approximately parallel with the plane of the skin side 5. At the time the blank 7 is cut or turned, a formed surface 8 may be provided on the blank at a fixed distance from the gauging points, so that a blank of the thickness defined by the testing operations may be obtained.

After the blank 7 is removed from the turning machine, the skin side 5 thereof or side engaging the gauging points 6 has a surface 9, shown in Figs. 9 and 10, formed thereon, and, if the blank is of a thickness to produce a plurality of disks, or blanks for buttons, or the like, then the blank is divided transversely and, during such division, one or both finished surfaces may be provided on the divided faces, if desired. The surfaces 8 and 9 are not necessarily provided in the manner above set forth as both surfaces can be placed upon the blank in the same

operation by machinery now in common use.

What I claim as my invention and desire to secure by Letters Patent is:

A method of producing buttons, or blanks 5 for disks, buttons, or the like from ivory nuts, which consists in testing irregularly shaped pieces, cut from ivory nuts, by a number of tests around the circumference of each at four spaced points to find or locate in each 10 piece the maximum possibilities in buttons or blanks obtainable therefrom with reference to diameter as related to thickness,

causing, in the final test, at four spaced points, each nut piece to assume the best position for obtaining therefrom the maximum desirable size of button or button blank, utilizing the four points determined by the final test for directing the nut piece to a cutting point, and cutting from the irregularly shaped nut piece, while so positioned, the button or blank as found or located by the final test. 15 20
